FLOW PROPORTIONING APPARATUS

Herbert Ziebolz, Chicago, Ill., assignor to Askania
Regulator Company, Chicago, Ill., a corporation
of Illinois

Application July 9, 1941, Serial No. 401,666

11 Claims. (Cl. 137—164)

This invention relates to improved apparatus for controlling the flow of combustion supporting air to a furnace.

Heretofore, it has been suggested that rates of fuel flow be summarized by means of fuel flow meters or by pilot air flows which are directly proportional to the individual B. t. u. rates of fuel flow and the total air proportioned to the sum of the individual fuel flows in terms of their heating values. The design of such mechanisms is based on the fact that a definite amount of air is required for theoretically complete combustion of a given quantity of fuel in terms of its B. t. u. value. In the operation of industrial furnaces or boiler furnaces a number of factors must be taken into consideration which render the supply of the calculated or exact amount of air necessary for theoretically complete combustion, improper. Such factors do not vary as a direct function of the rate of fuel flow but present different values at different rates of fuel flow. Some of these factors are, for example, air used to atomize liquid fuels or primary air used for conveying pulverized fuel, which air is not subject to control by the well known air control apparatus. Such factors may be termed "burner factors." The calculated amount of air, which would be supplied by the control apparatus to support theoretically complete combustion of a single fuel, modified by the amount of air which finds its way into the burner installation by reason of these factors, is referred to herein as "compensated air requirements" of that fuel. If more than one fuel is supplied, the calculated amount of air which would be supplied by the control apparatus to support theoretically complete combustion of the plurality of fuels, modified by the amount of air which finds its way into the burner installation, as a result of the feeding of more than one fuel, is referred to herein as "totalizer compensated air requirements" for the fuels. Further correction factors may be necessary in any furnace installation to take into account infiltration of air into the furnace, other sources of air of determinable amounts admitted to the furnace, or the desired condition of the furnace atmosphere. All of these factors are subject to variations which are not direct functions of the rate of total fuel supply. They may be termed furnace factors. These furnace factors may require further adjustment in the "total compensated air requirements" called for by the fuels. The total compensated air requirements, thus modified by these furnace factors, is herein termed "adjusted total air requirements."

It is therefore the main object of this invention to provide improved apparatus of the above type which will adjust the controlled supply of combustion air in accordance with varying fuel flow and other variable factors, such as those mentioned above.

Other aims and advantages of the invention will appear in the specification, when considered in connection with the accompanying drawing,

10 wherein:

Fig. 1 is a diagrammatic illustration of a summarizing mechanism embodying the invention and applied to two fluid fuels;

15 Fig. 2 is a top plan view of differential gearing of the type employed in Fig. 1; and

Fig. 3 is a diagrammatic illustration showing differential gears applied to the control of three fuels.

20 Referring particularly to the drawing, the apparatus there shown is applied to control the amount of combustion supporting air for separate fluid fuels, each of which is manually controlled and is subject to variations in quantity flow. In Fig. 1 there are shown two fuel conduits 10 and 11 and a single air conduit 12 through which air is supplied for the combustion of both fuels. All of the conduits lead to an ordinary furnace (not shown). Reference is here made to a patent to Ziebolz et al. No. 2,134,745, 25 wherein regulators are employed to proportion the flow of air to the flows of a plurality of separate fuels.

30 In the present instance, differential pressure flow impulses are produced on opposite sides of 35 restrictions in the fuel lines. These pressure differentials are transformed into movements which are directly proportional to the respective compensated amount of air for the fuels at different rates of flow. These movements, which do not have to be directly proportional to the B. t. u. 40 rates of flow, are transmitted to a summarizing device connected to control the flow of air. Herein, each of the conduits 10 and 11 has a constriction 13, on the opposite sides of which, are 45 connected pipes 14 and 15 leading to the opposite sides of a diaphragm 16 connected to act on one side of a pivoted jet pipe 17 of a differential pressure operated regulator of a well known type. The force exerted by the diaphragm acts in opposition to a spring 18, the compression of which is 50 controlled by a cam 19 of adjustable contour. Herein, the cam is shown as being composed of a multiplicity of relatively adjustable, slotted pieces clamped together by a bolt 20 and secured to a carriage 21 which is slidably mounted in

fixed bearings. The jet pipe regulator has an ordinary ratio slider 22 which may be employed to vary the ratio between the compensated air requirements for the fuel and the fuel flow, as will be described. The jet pipe is shown as delivering fluid to one or the other of two conduits 23 and 24 connected to operate a servo motor 25 of the piston type which, in turn, operates a gear 26 meshing with a rack 27 on the carriage 21. The carriage is shown as carrying a pointer 28 cooperating with an indicating scale 29 which indicates the compensated individual air requirements for the fuel, as called for by the carriage movements.

It will be seen that a force exerted by the diaphragm 16 on the jet pipe relay will move the jet pipe until the servo-motor operates the cam 19 and compresses spring 18 sufficiently to counterbalance the action of the diaphragm force and returns the jet pipe to its neutral position. Thus, a definite relation between the flow impulses and the movement of the cam, indicated by pointer 28, is established. This relation can be changed by varying the contour of the loading cam to compensate for varying factors which affect the burner performance, such as atomizing or primary air delivered with the fuel or air seepage into the fuel conduits and the burner. Such air may be delivered at a constant rate or may vary out of proportion to changes in the fuel load or rates of flow. The cam is thus adjusted to cause the impulse system to produce movements which are directly proportional to the compensated air requirements necessary to support complete combustion of the fuel at varying rates of flow but ignoring air infiltration through the furnace walls or the particular characteristic of the furnace.

From the above, it will be apparent that, regardless of the characteristic of a flow impulse which, in many cases, is not a second power function, it is always possible to produce a corresponding movement of the cam 19 which is directly proportional to the compensated air requirements of the individual fuels for a given rate of flow. More particularly, this arrangement permits adjustments to be made which take into account the burner characteristics and the amount of air delivered with the fuel at any rate of firing. For example, some burners require a constant amount of primary or atomizing air and others require amounts which are out of proportion to the fuel load. These conditions can be anticipated by means of the variable cams 19. In addition, the ratio sliders 22 permit the introduction of correction factors which take into account variations in the chemical analysis of the fuels, viscosity changes, density changes, temperature changes, etc. Any change in the position of the ratio sliders 22 increases or decreases the stroke of the cams directly proportional to the impulses throughout the flow ranges.

In the present instance, the movements of the cams, which are proportional to the compensated air requirements of the fuels, are transmitted through a summarizing device to a control valve for the air. Herein, each rack is shown as carrying a fixed arm 30 to which is pivotally connected an operating link 31. The operating links are connected in turn to cranks 32 which actuate shafts 33 carrying spur gears 34. The spur gears 34 operate a differential gear 35 which transmits rotary movement through a shaft 36 to a gear 37. The gear 37 operates a rack member or carriage 38, which is similar to the carriages 21 and carries an adjustable cam 39 simi-

lar to cams 19. This cam is shaped to take into account total air infiltration into the furnace and to vary the total compensated supply of air called for by the fuels under varying total fuel loads. It is also used to allow for either an excess or a deficiency of air throughout the fuel load range when the percentages of excess or deficiency are not directly proportional to the load. Further, it can be adjusted to allow for combustible gas generated in a furnace reaction calling for more air at different fuel loads. Likewise, it can allow for uncontrolled air delivered to the furnace from another source. In fact, the adjustment of this cam greatly influences the furnace operation or program. The carriage 38 is mounted similarly to the carriages 21 and is also shown as carrying a pointer 40 cooperating with a scale 41, to indicate the sum of the compensated air requirements of the separate fuels in addition to the compensation added by varying cam 39, because the movement imparted to the gear 37 and, through it, to the cam 39 represents the sum of the movements imparted by the separate cams through the differential gear.

Now, the flow of the air in conduit 12 is shown as being controlled by a butterfly valve 42 which is actuated by a piston type servo-motor 43. The servo-motor is connected by pipes 44 and 45 to be operated by a jet pipe 46, also having a ratio slider 47, whereby the ratio between the amount of air called for by the totalizing cam and the actual or the adjusted total amount of controlled air may be changed at will. The cam 39 acts on one side of the jet pipe through a spring 48 and changes the setting of the regulator to control the air flow through conduit 12. The spring 48 acts on the jet pipe in opposition to a diaphragm 49 on the opposite side of the jet pipe, and the position of the diaphragm is controlled by the pressure differential across a constriction 50 in the air conduit, acting through pipes 51 and 52 on opposite sides of the diaphragm.

As the spring 48 is compressed by the movement of the cam 39 to the right, the jet pipe turns clockwise and thereby causes the servo-motor to open the valve 42 until the increase in air flow creates a differential pressure across the constriction 50 which is sufficient to counterbalance the spring pressure. Thus, the air flow is so controlled that it is proportional to the air cam movement, which, in turn, is directly proportional to the sum of the individual compensated air requirements of the individual fuels, as further modified by the adjusted contour of cam 39. The adjustments of the ratio slider 47 permit variations in the ratio between the air flow called for by the cam 39 and the actual air flow, thus controlling the percentage of excess or deficiency of the total air.

As the flow of fuel 1 increases, for example, it will be understood that the regulator and the mechanism will impart movement to the left-hand link 31 and crank 32 to the right and, as the flow of fuel 2 increases, the right hand link and crank will likewise be moved to the right, thus transmitting counterclockwise movement to the gear 37 through the differential gear shaft 38. This moves the cam 39 to the right. The cam, in turn, moves the jet pipe 46 clockwise to operate the piston of the servo-motor 43 in a direction to open the valve 42 and thereby increase the flow of air. Then, the resistance to movement of the jet pipe is increased by an increased differential pressure acting on the diaphragm 49. When the differential pressure

counterbalances the spring pressure, the jet pipe automatically returns to its neutral position.

In Fig. 3 there is shown an arrangement of differential gears for transmitting summarizing movements in accordance with the compensated air requirements for three fuels. In that instance, the summarizing shaft 36 is connected to operate one of the two spur gear shafts 33' of the second differential gearing which has a differential gear shaft 36' carrying the gear 37. The other shaft 33' of the second differential gearing is connected to be operated by a link 31' which is actuated in response to the compensated air requirements for the third fuel. The operating means for the third link 31' may be similar to those shown for the two links 31 in Fig. 1. It will be understood that any number of fuels may be handled in this manner by adding to the number of differential gears. Furthermore, the mechanism will function satisfactorily if only one fuel is used at any given time.

Referring again to the mechanism shown in Fig. 1, it will be understood that the regulators, servo-motors and the cams may be mounted on any suitable support, such as a table. The stroke of the cams can be made the same for all controls by choosing the necessary gear ratios of the differential gears and the cams may be guided for straight line movement in any convenient manner, for example, by wheeled or sliding carriages or the like. Moreover, the compensated air requirement indicators may be either mechanical or electrical and all of them may be located at any convenient point.

Obviously, the present invention is not restricted to the particular embodiment thereof herein shown and described. Moreover, it is not indispensable that all the features of the invention be used conjointly, since they may be employed advantageously in various combinations and sub-combinations.

What is claimed is:

1. Apparatus for proportioning and controlling the supply of combustion air for at least two separate fuels which are subject to varying flows, comprising, in combination, individual conduits for the air and the respective fuels; means for producing controlling impulses respectively responsive to the rate of flow of each of the fuels; impulse operated systems, including movable elements and associated adjustable means, so connected as to produce movements of said elements which are directly proportional to predetermined amounts of air corresponding with different rates of fuel flow and theoretically necessary to support complete combustion of the fuels in the burner installation, said adjustable means being arranged to effect a departure from the proportional relation between said movements and the rates of fuel flow by a predetermined amount for each increment of change in the rate of fuel flow; a summarizing device connected to said movable elements to totalize said movements; control means for adjusting the supply of air through said air conduit connected for actuation by operation of said summarizing device; and means; forming a part of said air control means, to alter the effect of the operation of said summarizing device, said altering means being constructed and arranged to produce any predetermined, desired variation in the flow of air through said conduit, as effected by operation of said summarizing device for each increment of its total movement, whereby predetermined atmospheric conditions in a furnace may be obtained.

2. Apparatus for proportioning and controlling the supply of combustion air for any number of separate fuels comprising, in combination, individual conduits for the air and the respective fuels; means connected to the respective fuel conduits to produce impulses which are functions of the rates of the fuel flows; impulse operated systems, including movable control elements and associated manually adjustable means, so connected as to convert said impulses into controlling movements which are directly proportional to compensated air requirements which would support complete combustion of the respective fuels at varying rates of flow, said manually adjustable means being constructed and arranged to effect a departure from the proportional relation between said movements and the rates of fuel flow by a predetermined amount for each increment of change in the rate of fuel flow; summarizing means connected to said control elements; and air control means connected to be operated in response to the sum of said controlling movements transmitted through said summarizing means.

3. Apparatus for proportioning and controlling the supply of combustion air for any number of fuels comprising, in combination, individual conduits for the air and the respective fuels; means connected to the respective fuel conduits to produce pressure impulses which are functions of the rates of the fuel flows; impulse operated systems, including movable control elements and associated manually adjustable means, so connected as to convert said pressure impulses into controlling movements which are directly proportional to the compensated air requirements which would support complete combustion of the respective fuels at varying rates of fuel flow, said manually adjustable means being constructed and arranged to effect a departure from the proportional relation between said movements and the rates of fuel flow by a predetermined amount for each increment of change in the rate of fuel flow; differential gearing connected to said control elements to summarize said proportional movements; and air control means connected to be operated by said differential gearing in response to the summarized movements transmitted therethrough.

4. Apparatus as set forth in claim 1, wherein the impulse operated systems include fluid jet pipe regulators controlled by the impulses and the manually adjustable means comprises a loading cam of adjustable contour for each regulator connected to operate the control elements.

5. Apparatus as set forth in claim 1, wherein the impulse operated systems include fluid jet pipe regulators controlled by the impulses and servo-motors, operated by the regulators, are connected to transform the impulses into the movements, each regulator having ratio controlling means to vary the ratio between the fuel flows and the movements to take into account changes in the character of the fuels, such as the B. t. u. content, temperature, viscosity and other factors which vary in proportion to the fuel flows.

6. Apparatus as set forth in claim 1, wherein the impulse operated systems include servo-motors connected to said movable elements and indicators are associated with said elements to indicate amounts of air corresponding with and called for by said movements.

7. Apparatus as set forth in claim 1, wherein the summarizing device comprises differential

gearing connected to the movable elements, and the air control means includes a fluid jet pipe regulator which varies the supply of air delivered by the air conduit and the means to alter the effect of the operation of said summarizing device is a movable loading cam of adjustable contour operated by the differential gearing to control the regulator, the adjustments of said cam taking into account air infiltration into the furnace.

8. Apparatus as set forth in claim 1, wherein the summarizing device comprises differential gearing connected to the movable elements, and the air control means includes a fluid jet pipe regulator which varies the supply of air delivered by the air conduit and the means to alter the effect of the operation of said summarizing device is a movable loading cam of adjustable contour, operated by the differential gearing to control the regulator, and the regulator has a ratio varying element, the contour of the cam taking into account any uncontrolled air delivered to the furnace and the ratio varying element providing for any desired percentage of excess or deficiency of controlled air throughout the total fuel load range.

9. Apparatus as set forth in claim 1, wherein the air control means includes a fluid jet pipe regulator and the altering means is a loading cam of adjustable contour for the regulator connected to be operated by said summarizing device; and a ratio varying device is also associated with said regulator.

10. In apparatus of the class described for proportioning and controlling the supply of combustion air in accordance with a varying supply of fluid fuel, means connected to produce controlling impulses in response to varying rates of fuel flow; an impulse operated system, including a movable element, connected to produce movements of said element in response to changes in the rate of fuel flow which are directly proportional to predetermined amounts of air corresponding with different rates of fuel flow and theoretically necessary for complete combustion

of the fuel at said flow rates; manually adjustable means, forming a part of said impulse system, to vary said proportional relation between the movements and fuel flow at different rates and constructed and arranged to take into account factors which are not proportional to the fuel at different rates of fuel flow, such as air entrained with the fuel; means for supplying air through a conduit to burn the fuel; control means for varying the supply of air through said conduit connected to be actuated by said movable element; and means, forming a part of said air control means, to alter the effect of the operation of said movable element, said altering means being constructed and arranged to produce any predetermined desired variation in the flow of air through said conduit, as effected by operation of the movable element, for each increment of its total movement.

11. Apparatus for proportioning the flow of one fluid relative to a function of the flow of at least two additional fluids comprising, in combination, individual conduits for the fluids; means connected to the conduits for said additional fluids to create impulses which represent a function of the respective additional fluid flow rates; an impulse operated system, including movable elements, connected to said impulse means for each additional fluid flow to convert said impulses into movements of said elements which represent a function of but not necessarily directly proportional to the magnitude of the impulses; summarizing means connected to said last named means; and a hydraulic jet pipe regulator having a loading cam and being connected to control the flow of said first mentioned fluid, said cam being of adjustable contour and connected to be operated by said summarizing means to control the regulator, said cam also permitting variations in the ratio between the flow of the first fluid and sum of the flows of the additional fluids throughout the flow range.

HERBERT ZIEBOLZ.
